UNITED STATES PATENT OFFICE.

NATALIE MARJORIE BARLET, OF PHILADELPHIA, PENNSYLVANIA, ASSIGNEE TO THE JUNOFORM COMPANY, OF PHILADELPHIA, PENNSYLVANIA, A CORPORATION OF PENNSYLVANIA.

GARMENT.

1,144,631.

Specification of Letters Patent. Patented June 29, 1915.

Application filed July 5, 1913. Serial No. 777,525.

To all whom it may concern:

Be it known that I, NATALIE MARJORIE BARLET, a citizen of the United States, residing at Philadelphia, in the county of 5 Philadelphia and State of Pennsylvania, have invented certain new and useful Improvements in Garments, of which the following is a specification.

The invention relates generally to improvements in apparel, and particularly to drawers for ladies' use at such periods as may be necessary, the improved construction providing a highly sanitary article, readily adjustable as to size, and having means for 15 the convenient securing of the usual pad or cloth in place.

The main object of the present invention is the provision in an article of this class of a seamless and waterproof crotch section, 20 serving to protect the outer clothing against stains without adding in any way to the discomfort of the wearer.

A further object is the construction of the leg portions with the provision of means, 25 such as tying tapes or ribbons, whereby the article is adjustable to practically any size, an elastic waist band compensating for different sizes at that point.

In manufacturing articles of this kind it 30 has been found practically impossible to have them absolutely waterproof, owing to the necessity of having seams and consequently needle holes in the crotch portion of the garment and a resultant leaky construction; if the seams are stripped it adds 35 too greatly to the bulk of the garment. The present invention is designed to directly avoid these objections, and at the same time reduce the cost of manufacture, while providing a practically universally and automatically adjustable garment.

The invention in the preferred details of construction will be described in the following specification, reference being had 45 particularly to the accompanying drawings, in which:

Figure 1 is a perspective view illustrating the invention. Fig. 2 is a plan of the article, showing the same opened out, the waist band 50 being omitted. Fig. 3 is a section on the line 3—3 of Fig. 2. Fig. 4 is a broken perspective of a detail.

Referring to the accompanying drawings, the improved drawers may be said to comprise a crotch section 1 and duplicate waist

sections 2. The crotch section is made of an unbroken or integral strip of appropriate material having its minimum width midway between the ends, or at the center portion 3 of the garment, and is gradually increased 60 in width therefrom toward the ends 4. The portion of minimum width constitutes the crotch portion of the garment, passing between the legs of the wearer, it being understood that the crotch section is folded upon 65 itself at such central portion, so that the material of the crotch section in both directions beyond the central portion constitute the front and rear of the garment.

The waist sections 2, which are in effect 70 duplicates, preferably comprise panels 5 and 6 of suitable fabric, secured in endwise arrangement by stitching 7 uniting the overlapped ends. The meeting edges of the panels constituting each waist section are 75 cut away for a portion of their lengths, so that when the panels are secured together, an approximately V-shaped opening 8 is formed centrally of the upper edge of the section. The lower edges of the completed 80 waist sections are secured to the upper edges of the front and rear portions of the crotch section, the meeting edges of the waist and crotch sections being preferably slightly curved to insure a more comfortable fit. As 85 thus constructed the side edges of the crotch and waist sections are free of connection with each other throughout their entire lengths, the openings thus provided constituting leg openings. The upper edges 90 of the waist sections are lapped and stitched to provide draw-bands 9 in which is slidably arranged an elastic strip 10. The strip extends through the band of both waist sections, being terminally connected to 95 the rear waist section immediately adjacent and on each side of the opening 8 therein. The band or strip 10 thus unites the otherwise unconnected front and rear portions of the garment into garment-forming relation, 100 and constitutes the sole connection between the parts above the central portion. The leg openings thus extend practically throughout the full length of the garment, and as a means for adjustably closing them 105 to accord with the comfort and convenience of the wearer, I secure tapes 11 to the edges of the leg openings at the juncture of the leg and waist sections, which tapes may be tied in the usual manner to reduce the size 110

of the leg openings, as may be desirable. The edges of the leg openings below the tapes are provided with panel strips 12, which increase the width of the garment at 5 this point, and may if desired have an edge ornamentation, as shown.

As a salient and important feature of the present invention I treat the fabric forming the crotch section to waterproof the inner surface thereof, or more correctly form the crotch section of fabric which has one or both surfaces waterproofed, and arrange such fabric so that one such surface, as 13, constitutes the inner surface of the crotch section. This waterproof section is integral, wholly without seams, except at the ends and edges, and presents an unbroken, non-leaking protection throughout, particularly in the crotch where it is most needed. All seams at the crotch are avoided, hence needle holes and consequent liability of leakage cannot result. Any possibility of stains passing through the garment as thus constructed is obviated by this construction, and this together with the universal adjustment previously described renders the garment admirably adapted for the use intended.

Secured to the garment on the line uniting the leg and waist sections are loops 14, designed to serve as a means for attaching the usual pad or napkin in place. The pad is thus properly positioned with relation to the waterproof section at all times, so as to secure the most effective results from the latter. The V-shaped opening 8 of the rear waist section is provided with a loop and button connection 15 to unite said edges after the garment is in place, thereby securing more or less tension on the strip 10 to hold the garment in place.

The improvement provides a garment for

special uses in which the crotch portion, and in fact the entire portion underlying the pad or napkin is absolutely seamless and unbroken, whereby to perfectly prevent leaking; and further provides a practically universally adjustable garment without bulk which in itself has means whereby it may be comfortably adjusted to the particular wearer. 41 50

The improvement further serves a three-fold purpose, as it takes the place of the usual drawers, does away with the necessity for a sanitary belt to support the catamenial sack, as well as forming a perfect shield or sanitary apron for the prevention of the staining of outer garments. 55

Having thus described my invention, what I claim is:

As an article of manufacture, a device of the title described, including a water-proof member, in outline, flaring from a central narrow crotch portion, waist-panel forming members applied to the upper flared ends of said water-proof member, tying tapes interposed between said water-proof member and said waist-panel forming members, the upper edges of said waist-panel forming members having draw bands containing a slideable elastic member, the front waist-panel forming members having a separable connection therebetween, and lateral panel strips applied to the edges of said water-proof member, said lateral panel strips having outer edge upwardly flared formations and central constricted crotch portions.

In testimony whereof I affix my signature
in presence of two witnesses.

N. MARJORIE BARLET.
